UNITED STATES PATENT OFFICE.

LOYD S. McCORMICK, OF LEAVENWORTH, KANSAS.

COMBINATION HEEL STOP AND CUSHION.

Application filed May 29, 1922. Serial No. 564,569.

My invention relates to a combination heel stop and cushion to be worn inside of a shoe at the forward portion of the heel, and my primary object is to provide a device of this character for preventing the foot from slipping forward and crowding the toes into the relatively narrow forward portion of the shoe and thereby distorting the foot and causing pain and inconvenience.

10 In carrying out the invention, I employ a portion of an insole having a cushion at its underside formed to fit snugly against the forward portion of a person's heel to constitute a stop or abutment, said insole being 15 anchored to the inside of the shoe so that it will coat with the cushion in positively preventing the foot from moving forward in the shoe.

The present invention should not be confused with the numerous arch-supports on the market as it is not of a size or shape to conform to the arch of the foot. Neither is it intended to be worn beneath the heel, but, on the contrary, is designed solely for the 25 purpose of constituting a stop for the heel to prevent the foot from slipping forward in the shoe as above stated.

In order that the invention may be fully understood, reference will now be had to the 30 accompanying drawings, in which:

Fig. 1 is a longitudinal section of the device in position in a shoe.

Fig. 2 is a plan view of the device shaped to fit into the right shoe.

35 Fig. 3 is a rear elevation of the cushion.

Fig. 4 shows the opposite end of the cushion from that disclosed by Fig. 1.

In carrying out the invention, I employ a portion of an inner sole 2 consisting, preferably, of leather, although other flexible material may be employed. The insole 2 is provided at its under portion with a heel stop 4 constituting an important feature of the invention. Said heel stop 4 may be made of 45 any suitable material, porous sponge-like rubber being preferable as it is soft and comfortable for the foot. The stop 4 is cemented or otherwise fixed to the underside of the insole 2 and is of peculiar shape in

50 order to fit the forward portion of the heel of the user and constitute a stop or abutment for preventing the foot from slipping forward into the narrow forward portion of the shoe. As shown by the drawing, the 55 stop 4 curves rearwardly and gradually thickens from the outer side 6 to the inner

side 8 to fit into the hollow portion of the foot immediately in advance of the heel and which is higher at the inner side than at the outer side. The rear side 9 of the stop 4 extends upwardly in an abrupt manner as best shown by Fig. 4, to form an abutment against which the forward portion of the heel bears and is thereby positively prevented from slipping forward in the shoe.

In order to prevent the insole 2 and the stop 4 from slipping forward said insole 2 is anchored to the shoe A by suitable means, a thumb tack 10 being preferably employed.

In practice the devices are formed to fit 70 right and left shoes, the device shown by the drawing being formed to fit the right shoe.

By equipping the shoes with my devices the feet are prevented from slipping forward as hereinbefore stated and at the same time the wearer experiences no discomfort, owing to the shape of the stops 4 and their adaptability to the conformation of the forward portions of the heels against which said stops abut.

It is to be understood that the device is a complete article in itself and can be readily placed in the shoe or removed therefrom whenever desired. In some instances an entire insole may be substituted for the partial insole 2, or if desired the insole may be dispensed with, in which case the stop 4 would be cemented, tacked, or otherwise fixed to the inner portion of the shoe.

The device as a whole is simple, compact in construction, inexpensive to manufacture, and well adapted for the purpose intended, and the materials and finish of the several parts may be such as the judgment and experience of the manufacturer may dictate.

While I have shown and described the preferred construction and arrangement of the device, I reserve the right to make such changes therein as properly fall within the spirit and scope of the appended claim.

Having thus described my invention, what I claim and desire to secure by Letters Patent, is:

A device of the character described consisting of a resilient heel stop which is curved longitudinally and tapers towards one end, the rear wall of said heel stop extending upwardly abruptly to constitute an abutment.

In testimony whereof I affix my signature.
LOYD S. McCORMICK.
